UNITED STATES PATENT OFFICE.

HUGO KARL SAKOWSKI, OF HELSINGFORS, FINLAND.

CONTAINER FOR MATCHES, TOOTHPICKS, AND KINDRED ARTICLES.

Application filed April 13, 1925, Serial No. 22,788, and in Germany March 24, 1925.

The invention has reference to a container for matches, toothpicks, and kindred articles; and its chief object is to provide a container for articles of the character indicated which is of attractive appearance, handy for every day use of smokers and in the household, safe when carried in the pocket and when lighting matches, constructed for temporary use, low priced and having maximum space for advertisements.

An important point, with reference to the construction of the new container, is the extensive utilization of the spring action of the cardboard or other material of which the container is made, whereby a number of new and useful functions are produced.

One of the advantages of the improved container is that loose wooden, paraffin, paper or other matches are always kept in proper position, and prevented from sliding or moving in the pocket. For this purpose a holding device is arranged on the inside of the front wall of the container pocket, which device is made of the same material as the body of the container, so that the necessary spring action for the said holding device is thus provided. Additional spring action features are described in detail in the following specification.

Referring to the accompanying drawings:—

Figure 1 is a plan view of the unfolded blank from which the container is made;

Fig. 2 is a perspective view of a completed container opened;

Fig. 3 is a plan view of a closed container;

Fig. 4 is a longitudinal section of a closed container, on line A—B, Fig. 3;

Fig. 5 is a similar section on line C—D, Fig. 3;

Fig. 6 is a transverse section on line E—F, Fig. 3.

As represented in Fig. 1, it will be seen that the improved container is made from a single continuous strip or blank of cardboard or other suitable resilient sheet material which is divided by fold-lines or the like into six main sections or members, numbered 1 to 6 and constituting, successively and respectively, a reinforcing section or flap, a cover, a top section, a back, a front section and a holding device; the arrangement being such, therefore, that one entire surface of the strip (in this instance, the outer surface) may receive printed mat-

ter, which can be applied thereto at a single operation, so to say.

The reinforcing flap 1, which is of substantially the same size as the cover 2, is folded backward against the inner face of the latter and is glued, stitched or otherwise secured thereto, so that the double edges of the two-ply member thus formed provide adequate finger-hold in opening or closing the container. To prevent the flexibility of the cover from being impaired by the reinforcing flap, however, the said flap is made a trifle shorter than the cover, and the zone of attachment of the two is limited to what may be termed the inner or lower half of the flap, the upper or outer half being left free or unsecured. The latter half of the reinforcing flap may, indeed, be bent slightly away from the cover (Figs. 2, 4 and 5) so as to press against the upper portions of the matches or other articles when the cover is closed, thus tending to check their movement in the container.

The outer edge 2' of the two-ply part 1—2 may, if desired, be slightly curved or otherwise shaped, instead of being straight, as shown; and the adjacent corners 10, 11 and 10', 11' of said part may be, and preferably are, cut away for the purpose of preventing the edges of the said part from touching the fingers holding the container when opening and closing the same, as well as of giving the container an attractive appearance.

The top section 3 serves to connect the cover 2 and the back 4, and is relatively small or short as compared with those parts. It provides the space necessary for the expansion of the pocket hereinafter referred to, and it enables the double flap to remain flat, whereas the front and back of the pocket are caused to bulge outward when the pocket is filled. This pocket is formed by the coaction of the back 4 and front section 5, the latter part being folded inward toward the former and secured thereto at its side edges by metal wires, clamps, or other suitable means indicated at 20 and 21. It is to be observed, however, that such connection is limited to the upper portions of the said edges of the parts, and that the lower portions thereof are left free and unsecured (Fig. 2); the resilience or springiness of the cardboard causing the unsecured edges to move outwardly away from each other. This spring action is utilized,

on the part of the front section 5, to normally maintain in outwardly-projecting position a fastening tab or tongue 9, which is formed by cutting a suitably-shaped slit 5 in the lower portion of said section and which is initially forced outward by the pressure of the inner ends of the matches when the same are introduced into the pocket; such tab being directed toward the 10 upper end of the container so that it can engage the edge 2' of the cover. The lower portions of both members 4 and 5 are bulged or expanded by the spring action aforesaid, as indicated at 32 and 33 (Fig. 2), so that 15 their curved or rounded edges provide a convenient finger-hold, as will be apparent. The holding device 6, which constitutes the sixth and last section of the strip or blank, is located at the opposite end of the 20 latter from the reinforcing flap 1 and consists of a serrated or indented flap or extension which forms a series of members of triangular or other suitable shape. These members are adapted to be folded inward 25 against the inner face of the front section 5 along their base line 31, which, of course, is the junction line of the parts 5 and 6, and they are normally pressed back and held in that position by the matches when the container pocket is full, but as the matches are 30 withdrawn, the resilience of the members opposite causes them to move individually in an outward direction so that they finally extend laterally across the pocket (Fig. 6) 35 and thereby prevent sidewise movement of the remaining matches. It is to be understood, in this connection, that the pocket is designed to receive matches or similar articles in a loose state, as distinguished from 40 cards or sheets of matches, the matches filling the pocket and causing it to expand or bulge, such bulge decreasing as the pocket collapses consequent upon the removal of the matches.

45 The usual striking surface may be provided, and may be arranged either upon the lower portion of the outer face of the back 4, as indicated at 26 in Figs. 4 and 5, or upon the outer face of the cover 2 adjacent to its free edge 2', as indicated at 25 in Figs. 1, 3, 4 and 5. Both surfaces may be utilized, as represented in Figs. 4 and 5 or either surface alone, if desired. In both arrangements, it will be observed that the danger 50 of accidental ignition of the matches remaining in the pocket is practically eliminated, for in the case of the surface 26, the back 4 forms a protecting shield between

the lighted match and the matches in the pocket; and in the case of the surface 25, 60 that surface cannot be used until the container is closed.

As previously stated, one entire face of the strip or blank of cardboard can be utilized to receive printed matter in the form 65 of advertisements, etc.; and such matter can, of course, be applied thereto at a single operation. When the blank is folded and its parts fastened together as above described, to form the finished container, the printing 70 will appear upon the outer faces of the various parts, thus providing ample space for advertisements of comparatively large size.

I claim as my invention:

1. A container for loose matches and similar articles, comprising a continuous strip 75 of resilient sheet material consisting of six interconnected sections, to wit: a cover, a reinforcing flap of substantially the same size as the cover folded against and secured 80 to the inner face of said cover, a back, a relatively-small top section connecting the adjacent edges of the cover and back, a front section folded inward toward the back and coacting with the same to form a pocket 85 for the matches, and an inwardly-folded member on the front section adapted to press against the loose matches and hold them in place in the pocket.

2. A container, according to claim 1, in 90 which the holding member embodies a plurality of separate parts which are normally forced against the inner face of the front section by the pressure of the loose matches but which are individually movable in an 95 outward direction when the adjacent matches are withdrawn.

3. A container for loose matches and similar articles, comprising a continuous strip 100 of resilient sheet material embodying a back, a cover, a front section folded inward toward the back and secured thereto at its side edges, said front section and said back coacting to form a pocket for the matches, and a serrated member on the free 105 end of the front section, the teeth of which are folded within the pocket and normally forced against the inner face of said front-section by the pressure of the matches, but are individually movable in an outward direction when the adjacent matches are withdrawn.

In testimony whereof I have affixed my signature.

HUGO KARL SAKOWSKI.
